ENGINE ATTACHMENT

Cecil Mobray, Keyes, Okla.

Application March 17, 1932. Serial No. 599,506

5 Claims. (Cl. 123—119)

The present invention relates to an attachment for internal combustion engines and has for its primary object, to provide, in a manner as hereinafter set forth, means for conducting the fumes from the crank case of the engine into the carburetor, thereby materially increasing the efficiency of the engine and reducing the consumption of fuel.

Other objects of the invention are to provide an attachment of the aforementioned character which will be simple in construction, strong, durable, efficient and reliable in use and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:—

Figure 1 is a view in side elevation of an engine, showing an attachment in accordance with this invention mounted thereon.

Figure 2 is an elevational view of the main portion of the attachment mounted in position on the engine, a portion of the latter being shown in vertical section.

Figure 3 is a view in vertical section through the main portion of the device.

Figure 4 is a view in horizontal section, taken substantially on the line 4—4 of Figure 3.

Referring now to the drawings in detail, it will be seen that the embodiment of the invention which has been illustrated comprises a vertically disposed, substantially tubular casing which is designated generally by the reference numeral 1, said casing including comparatively large and small upper and lower portions 2 and 3, respectively, which are connected by a tapered portion 4 providing an inclined shoulder in the casing. The lower portion 3 of the casing 1 is insertable in the filling neck 5 of the engine 6, as illustrated to advantage in Figure 2 of the drawings. The engine illustrated is that of a Model A Ford automobile. The lower portion 3 of the casing 1 has formed thereon an external flange 7 engageable with the upper end of the filling neck 5 and functioning as a stop.

The upper portion 2 of the casing 1 is rounded, as at 8, and terminates in an upstanding neck 9. A cap 10 is mounted on the neck 9. The cap 10 may be the usual breather cap which is mounted on the filling neck 5 of the engine 6.

A nipple 11 projects laterally from the portion 2 of the casing 1 and provides means for con-

necting one end of a flexible conduit 12 to said casing. The other end of the flexible conduit 12 is connected to the air intake of the carburetor 13 of the engine 6.

In an upper portion of the casing, preferably substantially in the horizontal plane of the nipple 11, are the air intake openings 14 which are covered by the screens 15. An air regulating closure 16 of substantially C-shaped horizontal section is mounted for vertical sliding movement 60 in the upper portion 2 of the casing 1 for controlling the intake openings 14. Guides 17 are mounted vertically in the portion 2 of the casing and, in conjunction with said casing, define channels for the reception of the ends or vertical 65 marginal portions of the closure 16. The handle 18 projects from the closure 16 and is operable in a vertical slot 19 provided therefor in the casing 1.

A baffle 20 is mounted on the shoulder 4 in the 75 casing 1 to prevent the splashing of the oil from the crank case of the engine, said crank casing being designated by the reference numeral 21. The baffle 20 is substantially in the form of an inverted cup and has its lower portion provided 80 with the substantially V-shaped notches 22 providing passages for the oil fumes.

It is believed that the many advantages of an attachment constructed in accordance with the present invention will be readily understood, and 85 although the preferred embodiment of the invention is as illustrated and described, it is to be understood that changes in the details of construction and in the combination and arrangement of parts may be resorted to which will fall 90 within the scope of the invention as claimed.

What is claimed is:—

1. An engine attachment comprising a casing connected with the crank case of the engine and communicating therewith for receiving the fumes 95 therefrom, said casing having air inlet openings therein, a conduit connecting the casing with the carburetor of the engine for delivering the fumes and air thereto, guides mounted longitudinally in the casing, and a substantially C-shaped 100 closure slidably mounted in the casing and engaged with the guides, said closure providing means for controlling the air inlet openings.

2. An engine attachment comprising an elongated, substantially tubular casing mounted vertically on the filler neck of the crank case of the engine and communicating with said crank case for receiving oil fumes therefrom, said casing having air inlet openings in an upper portion 105 thereof, a flexible conduit connecting the casing 110

with the carburetor of the engine for the delivery of air and the fumes thereto, guides mounted vertically in the casing, a substantially C-shaped closure for controlling the air inlet openings, slidably mounted for vertical movement in the casing and operatively engaged with the guides, and means for manually actuating the closure.

3. An engine attachment comprising an elongated, substantially tubular casing, said casing including comparatively large and small upper and lower portions, respectively, and a tapered connecting portion, said connecting portion providing a shoulder in the casing, the free end portion of the lower portion being insertable in the filling neck of the engine crank case for mounting the casing in vertical position thereon for receiving fumes from said crank case, a conduit connecting the casing with the carburetor of the engine, and a splash shield mounted in the casing, said splash shield being substantially in the form of an inverted cup mounted on the shoulder in the casing and having notches in its lower portion providing passages for the fumes.

4. An engine attachment comprising an elongated, substantially tubular casing, said casing including comparatively large and small upper and lower portions, respectively, and a tapered connecting portion, said connecting portion providing a shoulder in the casing, the free end portion of the lower portion being insertable in the filling neck of the engine crank case for mounting the casing in vertical position thereon for receiving fumes from said crank case, a conduit connecting the casing with the carburetor of the engine, and a splash shield mounted in the casing, said splash shield being substantially in the

form of an inverted cup mounted on the shoulder in the casing and having notches in its lower portion providing passages for the fumes, said casing having air inlet openings in an upper portion thereof, guides mounted vertically in the casing, a substantially C-shaped closure for controlling the air inlet openings, mounted for vertical sliding movement in the casing and operatively engaged with the guides, and means for actuating the closure.

5. An engine attachment comprising an elongated, substantially tubular casing, said casing including comparatively large and small upper and lower portions, respectively, and a tapered connecting portion, said connecting portion providing a shoulder in the casing, the free end portion of the lower portion being insertable in the filling neck of the engine crank case for mounting the casing in vertical position thereon for receiving fumes from said crank case, a conduit connecting the casing with the carburetor of the engine, and a splash shield mounted in the casing, said splash shield being substantially in the form of an inverted cup mounted on the shoulder in the casing and having notches in its lower portion providing passages for the fumes, said casing having air inlet openings in an upper portion thereof, guides mounted vertically in the casing, a substantially C-shaped closure for controlling the air inlet openings, mounted for vertical sliding movement in the casing and operatively engaged with the guides, and means for actuating the closure.
